UNITED STATES PATENT OFFICE.

FRANK DU B. JAQUETTE, OF ALTA, MONTANA.

MACHINE FOR AERIAL NAVIGATION.

Application filed April 23, 1925. Serial No. 26,502.

This invention relates to aerial navigation and relates more particularly to the propelling mechanism, the object being to provide an efficient mechanism by the use of which the ascent of the machine will be quickly accomplished and the descent thereof may be made safely. The invention is illustrated in the accompanying drawings and will be hereinafter fully set forth.

10 In the drawings:

Figure 1 is a plan view, partly broken away, of an air-navigating machine embodying my invention;

15 Fig. 2 is an end view of the same with parts in section;

Figs. 3 and 4 are side elevations of the blade or vane-carrying wheels showing the position of the blades or vanes at different stages in the operation of the device;

20 Fig. 5 is an enlarged detail section on the line 5—5 of Fig. 3, and

Fig. 6 is a similar view on the line 6—6 of Fig. 3.

Fig. 7 is an enlarged detail view of the 25 blade in part section.

The body 1 of the machine may be of any standard or approved type and is equipped with landing wheels 2 as is now the usual practice. A motor, indicated conventionally at 3, is mounted in the body and is geared to a front propeller 4 and a rear propeller 5 in order to control the movements of the machine. Rising from the body is an upper frame 6 and in the top of said frame are pivotally mounted transversely disposed plates 7 which constitute rudders whereby the machine will be directed into an ascent or a descent. These rudders may be manipulated from a point within the body of the machine through a lever, indicated at 8, and belt and pulley gearing, indicated at 9, connecting the lever in an obvious manner with the pivots of the rudders. If the rudders be tilted so that their under surfaces are presented to the wind, the machine will, of course, be directed into an ascent and, if they be tilted so as to present their upper surfaces to the wind, the machine will be directed into a descent. When the rudders are set horizontally, the machine will maintain an even keel.

Secured to the body 1 in any convenient or preferred manner and extending to the opposite sides thereof are a plurality of frames

10, in the outer ends of which are carried 55 gangs of propellers each consisting of a plurality of blades or vanes 11 and controlling wheels 12 and 13 connected therewith. In the accompanying drawings, I have illustrated these propellers arranged to operate 60 in vertical planes so that they exert force to lift the machine and maintain it in the air, but it is to be understood that they may be arranged, without departing from the invention, to operate in horizontal planes so 65 that they will exert force to propel the machine in either direction. The supporting frames 10 are, of course, rigidly connected with the sides of the body 1. In the outer ends of the frames are secured supporting 70 bars, each of which consists of an end member 14 angular in cross section so that it may fit within the extremity of the frame and be held therein against rotation. Immediately adjacent this end portion is a bearing portion 15 of circular cross section upon which a wheel 12 is mounted for free rotation, while at the inner end of the said bearing 75 portion is an offset or crank 16 which extends in a plane parallel with the plane of 80 the respective wheels 12 and 13 and between said wheels, as shown most clearly in Fig. 5. At the end of the offset or crank 16, an elongated portion 18 extends inwardly parallel 85 with the bearing member 15, and this elongated portion 18 is circular in cross section so as to provide a bearing for the hub of the wheel 13, as shown in Fig. 5. The construction just described is duplicated at the opposite side of the propeller device, it being understood that the wheels 12 and 13 are provided in pairs with each pair of wheels 13 being disposed between the wheels 12 constituting a pair, as will be readily understood upon reference to Fig. 1 of the drawings. To facilitate the assembling of the parts, the member 18 is divided and the opposed meeting ends of the axially aligned portions 18 are connected by a coupling 90 sleeve 19, as clearly shown in Fig. 5. To reduce the frictional wear and resistance, anti-friction members 20 are provided within the hubs of the several wheels 12 and 13 to run upon the bearing supports 15 and 18, as will 95 be readily understood. A sprocket wheel 21 is secured to or formed integral with the side of the hub member of each wheel 12, and these sprocket wheels are operatively 100 105

connected by chains 22 with a driving shaft, indicated at 23, mounted within or upon the body 1 and driven from the motor 3, as will be understood upon reference to Figs. 1 and 2.

At intervals in the rim of each wheel 12 are provided sockets 24 constituting bearings for the pintles 25 provided at the outer ends of cranks 26, which cranks are provided 10 with similar pintles or bearing members 27 adjacent their free ends, the aligned pintles 27 being connected by a bar 28 which is of angular cross section and upon which the blades or vanes 11 are mounted so that, while 15 the blades or vanes may revolve around the center of the wheel 13, they will be held against rotation about their own axes. The cranks 26 are of the same length as the cranks 16 and, of course, extend in the same 20 direction so that all the cranks lie in parallel planes at all times but the outer cranks 26 may be somewhat lighter than the inner cranks 16, as will be understood upon reference to Figs. 5 and 6. The wheels 12 and 13 25 may be of any preferred construction and are illustrated as consisting of a circular rim connected with the central hub through spokes, this construction being light and possessing sufficient strength but, if desired, the 30 wheels may be of disk form.

Each blade or vane includes a box 30 which is clamped upon the bar 28 adjacent the rim of the respective wheel 13 and thereby holds the wheel against lateral movement, and a stop collar 31 is secured upon the supporting member 18 adjacent the hub of the wheel for the same purpose. Secured to the boxes 30 and preferably integral therewith is a base bar 32 to the upper edge of which is secured a side frame 33 constituting the end member of a blade or vane. The upper edges of the side members 33 are arcuate and they may, if desired, be covered with fabric, as indicated at 34. 40 Extending transversely between the side members 33 are bars 35 and a fabric covering 36 is extended between adjacent bars alternating with valves or doors 37 which likewise extend between adjacent bars, as 45 shown most clearly in Fig. 7. These valves or doors 37 may be of sheet metal and are hinged at one edge adjacent one bar 35 and connected with the next succeeding bar 35 by a chain or other flexible connection 38. 50 During the downward movement of a blade or vane, the doors or valves 37 will be held in the closed position shown in Fig. 7 by the pressure of the air so that the blade will exert a lifting force upon the machine but, when the blade is moving upward, the pressure will cause the valves to swing downwardly to the limit of the connections 38 so that the resistance to the upward movement of the blade will be minimized. 55 It will be seen at once that the blades or

vanes are provided in gangs which are supported between wheels disposed eccentrically to the power-transmitting wheels, the inner cranks 16 forming the main supporting members for the blade-carrying wheels and the outer cranks 26 constituting connections whereby the rotation of the propelling wheels 12 will be transmitted to the blade-carrying wheels 13 to effect travel of the blades or vanes about the axes of the wheels 70 while retaining the eccentric relation of the wheels and causing the blades to maintain a horizontal position at all times. It will be readily seen that, when the blade or vane is traveling above or below the center of the propelling wheels, it is moving principally forwardly or rearwardly so that it encounters minimum resistance from the air and, when it is at the side of the wheel, it encounters the maximum resistance from the air 80 so that when it is moving downwardly it utilizes the pressure to sustain the machine in flight and when it is moving upwardly the valves 37 open so as to minimize the resistance and permit the blades or 85 vanes to move easily. It will be understood, of course, that the propellers may be set to rotate in any desired direction.

Having thus described the invention, I claim:

1. The combination of a supporting frame, a crank member secured rigidly in said frame, power wheels mounted for free rotation on the end portions of the crank member, a pair of wheels mounted for free rotation upon the central portion of said crank member, crank members connecting the rims of the first-mentioned wheels with the rims of the second-mentioned wheels at intervals and rotatably engaged in both 100 rims, and vanes secured on the last-mentioned crank members between the second-mentioned wheels and held against rotation on said crank members.

2. The combination of a supporting frame, a pair of wheels mounted thereon, a second pair of wheels mounted between the first-mentioned wheels in eccentric relation thereto, connections between the wheels whereby rotation of the first-mentioned wheels will effect simultaneous rotation of the second-mentioned wheels about their respective axes, vanes carried by and between the second-mentioned wheels and held against rotation about their own axes, said 115 vanes having arcuate tops provided with openings therethrough, and downwardly opening valves on said tops normally closing the openings.

3. In a machine for aerial navigation, the combination of a supporting frame, a crank member secured in said frame, power wheels mounted for free rotation upon the end portions of said crank member, a pair of wheels mounted for free rotation about the 120

central portion of said crank member, crank members connecting the peripheries of the wheels at intervals, frames secured to the last-mentioned crank members between the 5 second-mentioned wheels and held against rotation about said crank members, said frames having arcuate upper portions, a covering secured upon the arcuate upper portions of said frames and having openings therethrough, and downwardly opening 10 valves mounted below said covering and normally closing said openings.

In testimony whereof I affix my signature.
FRANK DU B. JAQUETTE. [L. S.]
